UNITED STATES PATENT OFFICE.

DANIEL S. McELROY, OF SPRINGFIELD, ILLINOIS.

ADDING OR CALCULATING MACHINE.

1,308,548.

Specification of Letters Patent.

Patented July 1, 1919.

Application filed November 6, 1917. Serial No. 200,479.

To all whom it may concern:

Be it known that I, DANIEL S. McELROY, a citizen of the United States, residing at Springfield, in the county of Sangamon and State of Illinois, have invented certain new and useful Improvements in Adding or Calculating Machines, of which the following is a specification.

The present invention has to do with certain improvements in adding or calculating machines and the like. More particularly it has to do with the construction of a machine of the non-listing type, although, as will presently appear, the features of the invention are in no wise limited to use in connection with non-listing machines. As a matter of convenience in illustration and description, I have shown a particular construction in which the features are embodied in a non-listing machine, but I wish it distinctly understood that, in so doing, I do not limit myself to their use in connection with this type of machine, except as I may limit myself in the claims.

One of the objects of the invention is to provide a very simple construction of machine, and one which can be manufactured very cheaply with the use of a comparatively small number of parts. Another object is to so construct the machine as to adapt it to rapid operation. Another object is to provide a simple and improved type of carrying mechanism for carrying tens to the higher orders.

Other objects and uses of the invention will appear from a detailed description of the same which consists in the features of construction and combinations of parts hereinafter described and claimed.

Referring to the drawings:

Figure 1 shows a cross section through the machine taken at a point between the operating and adding disks for two orders, being a section taken on the line 1—1 of Fig. 3, looking in the direction of the arrows. In Fig. 1, the parts are shown in the position which they normally occupy, none of the keys being depressed;

Fig. 2 is a fragmentary view similar to that of Fig. 1, with the exception that the five-key has been depressed for the order illustrated, and the accumulating wheel has been lowered into adding position, although the adding disk is shown in the zero or initial position;

Fig. 3 shows a horizontal or plan view of the machine shown in Fig. 1, the same being provided with the necessary operating, accumulating, and carrying mechanisms for three orders, and the top of the machine including the operating keys being removed so as to reveal the interior construction;

Fig. 4 shows a fragmentary detail section on enlarged scale taken on the line 4—4 of Fig. 3, looking in the direction of the arrows;

Fig. 5 shows a view similar to that of Fig. 2, with the exception that the adding disk has rotated to the position where it is stopped or arrested by the five key, thereby accumulating five ordinals into the accumulating wheel;

Fig. 6 is a fragmentary detail of the locking pawl which holds the adding disk in the zero position until the numeral pin or key has been fully depressed; and

Fig. 7 is an enlarged detail of the stops or rests for insuring a stoppage of the adding and operating disks at the zero position when the keys are all released.

Before explaining in detail the construction of machine herein disclosed, I will state that, in the present case, I have shown only three sets of numeral keys, and three sets of operating disks, adding disks, accumulating wheels, carrying mechanism and associated parts corresponding to three numerical orders. It will be understood, however, that the number of sets of parts to be provided will depend entirely upon the desired capacity of the machine, and I have shown three sets of parts simply by way of illustration.

Bearing the foregoing facts in mind, I will now refer to the construction shown in the drawings. In this case, there is provided a base plate 11 and a back plate 12 to which the main operative parts or bearings for them are connected. I have also shown a front plate 13 to which certain of the parts are journaled, and a top plate 14 to which certain additional parts are journaled. I have also shown a curved or arcuate key plate 15 within which are mounted the numeral keys or stems.

Extending transversely of the machine is a rod or shaft on which are mounted the numeral disks and the operating disks. The operating disks for the three orders indicated are numbered 17, 18, and 19, respec-

tively, and the corresponding numeral disks are numbered 20, 21, and 22, respectively. It will be understood that all of these disks are freely mounted on the rod or shaft 16, so that 5 they can rotate independently of each other.

Corresponding to each set of disks is a row or set of operating cams 23 for the numerals from one to nine, inclusive, in the particular order under consideration. These 10 cams 23 are conveniently mounted upon or formed as portions of the stems 24 on which are the numeral keys 25. Springs 26 are provided for the various numerals, which 15 springs, by raising the numeral keys and stems, simultaneously raise the cams 23.

On each of the operating disks there is a set of pins or contacting portions 27 corresponding to the various numeral cams for such disk, so that upon depression of any 20 one of the numeral keys of that order, that operating disk will be rocked on the shaft 16 a given distance by the engagement of the corresponding cam 23 with the corresponding pin 27. In Figs. 2 and 5, the five- 25 key has been depressed, so as to rock the operating plate or disk such distance.

On each operating disk is a pin or contacting portion 28 which rests against a lever arm 29 pivoted to a fixed portion at the point 30 30. A spring 31 has its ends connected, respectively, to the corresponding lever 29 and the corresponding adding disk, so that said spring tends to rock the adding disk in the direction of the arrow of Fig. 1. As soon 35 as any one of the numeral keys for that order is depressed, the corresponding lever 29 is tilted through a considerable angle, as shown in Fig. 2, so as to materially stretch the spring 31, and thereby place a consider- 40 able tension on the same tending to rock the adding disk in the direction of the arrows.

On each adding disk is a stop pin or the like 32. When the adding disk stands at the zero or normal position, this stop pin 32 is 45 engaged by a pawl or dog 33 which holds it against rotation. Upon disengaging the pawl from the stop pin, the adding disk is permitted to rotate forwardly or in the direction of the arrow under the impulse of 50 the spring 31 until the stop pin 32 strikes the lower end of the numeral pin 24 which was previously depressed, thereby arresting the further movement of the adding disk. By 55 this arrangement the adding disk is permitted to run forward a distance dependent upon and determined by the particular numeral key which was depressed. Suitable means presently to be described is provided for disengaging the pawl or dog 33 from the 60 stop pin 32 at the proper instant.

Corresponding to each adding disk is an accumulating wheel 34 into which the numerals are accumulated. Each accumulating 65 wheel has a number of teeth equal to, or a multiple of, the numeral at which the car-

rying takes place. In the decimal system, each accumulating wheel should have ten teeth or a multiple thereof. On each adding disk is a set of pins 35 which are correctly spaced to consecutively engage with the 70 teeth of the corresponding accumulating wheel for the purpose of adding numbers thereinto. Ordinarily there will be nine pins on each adding disk, but a tenth pin may be provided if desired. 75

Each accumulating wheel must be successively engaged with and disengaged from the pins of the corresponding adding disk, so that numerals added on the forward stroke will not be immediately subtracted on the return stroke of the adding disk. For this purpose, there is provided corresponding to each accumulating wheel a lever 36 pivoted on a rod 37, the accumulating wheel being pivoted on the forward end of said lever at 80 the point 38. A link 39 connects each lever 36 to the corresponding operating disk by the pivotal connections 40 and 41. By the use of this arrangement, the forward rocking of the operating disk, under the impulse of one 85 of the numeral key arms 23, will simultaneously tilt the lever 36 so as to bring the corresponding accumulating wheel into engagement with the pins 35 just before the disengagement of the pawl 33 from the stop pin 90 32. Thereafter, when said disengagement of the pawl takes place, and the adding disk is allowed to run forward, the numeral will be accumulated into the accumulating wheel. On the back stroke, the disengagement of 100 the accumulating wheel from the pins 35 will take place just before the backward movement of the adding disk commences, so that the numeral thus added in will not be immediately subtracted. 105

As a convenient construction for operating the pawls 33, I have shown the following arrangement: Each of said pawls is pivoted to a stationary part at the point 42, a spring 43 normally depressing the pawl into 110 the full line position of Fig. 6. A pin 44 is secured to each of the operating disks, said pin engaging a cam surface 45 on the lower face of the pawl. As the operating disk is rocked forward by the depression of one of 115 the numeral keys, its pin 44 will raise the pawl at the exact instant desired for the accomplishment of the results previously explained.

For each operating disk is a main spring 120 46 having one end connected to a stationary part at the point 47, and the other end connected to the operating disk through the medium of a pin 48. Each main spring is sufficiently powerful to restore the operating disk to the initial position upon releasing the numeral key which was previously depressed.

Corresponding to each adding disk is a lever 49 pivoted to a stationary part at the 130

point 50. A spring 51 serves as a yielding connection between said lever and the corresponding adding disk, one end of the spring being connected to the lever at the 5 point 52 and to the adding disk at the point 53. On the back stroke of the operating disk, its pin 48, or any other suitable contacting device, will engage the lever 49 and rock the same into the position shown in 10 Figs. 1 and 2, thereby placing the corresponding spring 51 under tension and restoring the adding disk to the initial position as soon as the lever 29 is permitted to rise by the rising of the pin 28.

15 The adding and operating disks carry the stop pins 53 and 54, respectively, which stop pins engage the fixed stops 55 and 56, respectively, as shown in Fig. 7, when the disks are at the initial position.

20 Means should be provided for carrying tens to higher orders, and I have provided a simple form of such carrying means, as shown particularly in Figs. 1, 2, 4, and 5. The accumulating wheel for the lowest or 25 units order meshes directly with the pinion 57 mounted on a short stub shaft 58, on the other end of which stub shaft is a ratchet wheel 59. A pawl or dog 60 pivoted at the point 61 and maintained in engagement 30 with the ratchet wheel by a spring 62 serves to prevent a reversal of direction of the accumulating wheel 57 by reason of the shaft 58. The pawl or dog 60 is similar in form and function to the pawls 66 and 35 is located in line with them.

The accumulating wheel for the units order carries a sidewise projecting pin 63 which is adapted to engage one of the teeth of the ratchet wheel 64 mounted on a stub shaft 65 each time the units accumulating 40 wheel completes one revolution, to thereby ratchet or notch up the wheel 64 one notch upon the completion of each revolution of the units accumulating wheel. A pawl or 45 dog 66 pivoted at the point 67 is maintained in engagement with the ratchet wheel 64 by a spring 68 so as to prevent reversal of said ratchet wheel and the shaft 65. On the other end of the stub shaft 65 is a pinion 69 which meshes with the accumulating 50 wheel 70 of the next higher or tens order at all times. Consequently each time the units accumulating wheel completes one revolution, the tens accumulating wheel will 55 be advanced one numeral by reason of the engagement of the units pin 63 with the tens ratchet wheel 64.

A similar series of connections is provided from tens to hundreds, from hundreds to thousands, etc., according to the 60 capacity of the machine.

As a matter of convenience in construction, the shafts 58, 65, etc., are used to provide the pivotal points 37 on which are 65 mounted the rock levers 36, by means of

which the accumulating wheels are successively raised and lowered to disengage them from and engage them with the adding pins 35 of the adding disks.

Numerals may be marked or otherwise 70 formed either on the various accumulating wheels or on drums connected to and operated by them. In the arrangement shown in the drawings, the latter scheme is illustrated as clearly appears from examination 75 of Fig. 3.

Examination particularly of Fig. 4 reveals the presence of sleeves 71 on which the levers 36 and the pawls 33 are mounted. These sleeves are also directly carried 80 by the downwardly depending lugs 72 which are connected to the upper portion of the casing of the machine. The sleeves serve not only as supports for the levers and pawls, but also as journals for the stub 85 shafts 58, 65, etc. This construction very materially reduces the friction of the parts on each other, and, therefore, makes it possible to produce a machine which will be extremely easy and, therefore, rapid in its 90 operation.

While I have herein shown and described only a single embodiment of the features of my invention, still it will be understood that I do not limit myself to the said embodiment except as I may do so in the claims. 95

I claim:

1. In a machine of the class described, the combination with a fixed shaft, of a plurality of adding segments journaled thereon, an operating segment journaled on said shaft adjacent to each adding segment, an accumulating wheel corresponding to each adding segment, teeth on each adding segment adapted to mesh with the teeth of the corresponding accumulating wheel, nine numeral keys corresponding to each operating segment, instrumentalities in conjunction with each numeral key for advancing the operating segment a predetermined distance when said numeral key is depressed and simultaneously setting a stop for arresting movement of the adding segment at the corresponding numerical position, a yielding operating connection from each operating segment to the corresponding adding segment, means for placing the same under tension when the operating segment is advanced as aforesaid, means locking each adding segment against forward movement until its operating segment has been moved forward by depression of a key, a yielding restoring connection from each operating segment to the corresponding adding segment, means for placing the same under tension when the operating segment is returned to its initial position, tension means for returning each operating segment to its initial position, an operative connection from each operating segment to the 115

120

125

130

- accumulating wheel of the corresponding adding segment for successively moving said accumulating wheel into and out of position for engagement by the adding teeth 5 of the adding segment, and carrying mechanism in conjunction with the accumulating wheels for carrying tens, substantially as described.
2. In a machine of the class described, the combination with a fixed shaft, of a plurality of adding segments journaled thereon, each having adding teeth, an operating segment journaled on the shaft adjacent to each adding segment, a yielding operating 10 connection between each operating segment and the corresponding adding segment, means locking each adding segment against forward movement until its operating segment has been moved forward by depression of a key, a yielding restoring connection between each operating disk and the corresponding adding disk, tension means for restoring each operating segment to normal position, numeral keys corresponding 15 to each operating segment for rocking the same, operating means between each adding segment and the numeral keys therefor for arresting movement of the adding segment at a position predetermined by the numeral 20 key depressed, an accumulating wheel corresponding to each adding segment, means for moving each accumulating wheel into and out of operative engagement with the teeth of its adding segment according to 25 the movements of the operating segment, and means in conjunction with the accumulating wheels for carrying tens, substantially as described.
3. In a machine of the class described, the combination of a plurality of adding segments mounted for rotation, each having adding teeth, an operating segment oscillatably mounted adjacent to each adding segment, a yielding operating connection 30 between each operating segment and the corresponding adding segment, means locking each adding segment against forward movement until its operating segment has been moved forward by depression of a key, a yielding restoring connection between each operating segment and the corresponding adding segment, tension means for restoring the operating segments to normal position, numeral keys in conjunction with 35 each operating segment, means in conjunction with each operating segment and its numeral keys for rocking the operating segment a predetermined distance each time a numeral key is depressed, means in conjunction with each adding segment and the corresponding numeral keys for arresting movement of the adding segment at a point predetermined by the numeral key depressed, an accumulating wheel for each 40 adding segment, teeth on each adding seg- 45 ment for the corresponding accumulating wheel, means for moving the accumulating wheels into and out of engagement with the teeth of their respective adding segments according to the movements of the operating segments, and means in conjunction with the accumulating wheels for carrying tens, substantially as described.
4. In a machine of the class described, the combination with a series of adding segments and accumulating wheels in conjunction therewith, of an operating segment adjacent to each adding segment, a yielding operating connection from each operating segment to the corresponding adding segment, means locking each adding segment against forward movement until its operating segment has been moved forward by depression of a key, a yielding restoring connection between each operating segment and the corresponding adding segment, tension means for restoring the operating segments to normal position, means in conjunction with the accumulating wheels for carrying tens, and numeral keys in conjunction with each operating segment and the corresponding adding segment for moving the operating segment when any numeral key is depressed and arresting the corresponding adding segment at the position determined by the said numeral key, substantially as described.
5. In a machine of the class described, the combination of a series of adding segments and operating segments corresponding thereto, a set of numeral keys corresponding to each operating segment, cam connections between the numeral keys and each operating segment for moving the operating segment a predetermined amount when any numeral key is depressed, means locking each adding segment against forward movement until its operating segment has been moved forward by depression of a key, means in conjunction with each numeral key and the corresponding adding segment for the purpose of arresting movement of the adding segment at the point predetermined by such numeral key, an accumulating wheel in conjunction with each adding segment, means for moving the arresting means into and out of operative engagement with their respective adding segments, and means in conjunction with the adding segments for carrying tens, substantially as described.
6. In a machine of the class described, the combination of a series of adding segments, an operating segment corresponding to each adding segment, an accumulating wheel corresponding to each adding segment, a yielding operating connection joining each operating segment and the corresponding adding segment, numeral keys in conjunction with each operating segment, means in conjunction with each operating segment and

- its numeral keys for moving the operating segment through a predetermined distance when any numeral key is depressed, means for locking each adding segment against movement until the operating segment is so moved, means for arresting the movement of each adding segment when the operating segment is so moved at a position predetermined by the numeral key depressed, and means in conjunction with the accumulating wheels for carrying tens, substantially as described.
7. In a machine of the class described, the combination with a series of adding segments mounted for oscillation on centers in alignment with each other, of bearing members intermediate the positions of said segments, sleeves rotatably mounted in said bearing members, stub shafts rotatably mounted in said sleeves, a ratchet wheel on one end of each stub shaft, a pinion on the other end of each stub shaft, a lever pivotally mounted on each sleeve adjacent to the pinion, a carrying wheel pivotally mounted on each lever and meshing with the adjacent pinion, and teeth on each adding segment adapted to engage the corresponding adding wheels, and means for oscillating the levers to carry the adding wheels alternately into and out of engagement with the adding segments, substantially as described.
8. In a machine of the class described, the combination of a series of adding segments and operating segments corresponding thereto, a set of numeral keys corresponding to each operating segment, means in conjunction with each operating segment and its numeral keys for moving the operating segment through a predetermined distance when any numeral key is depressed, an operative connection between each operating segment and its adding segment, means for locking each adding segment against movement until the operating segment is so moved, means for arresting the movement of each adding segment when the operating segment is so moved at a position predetermined by the numeral key depressed, means for disengaging said locking means when the operating segment is fully moved, and means in conjunction with the adding segment for accumulating numbers corresponding to their movements, substantially as described.
